UNDERFEED STOKER

Eric H. Smith, Worcester, Mass., assignor to Riley
Stoker Corporation, Worcester, Mass., a cor-
poration of Massachusetts

Application November 27, 1943, Serial No. 511,963

5 Claims. (Cl. 110—44)

This invention relates to underfeed stokers for the burning of fuel, and more particularly to the construction and arrangement of the reciprocable pusher blocks which are used for advancing the fuel along the retorts of such stokers.

An underfeed stoker comprises an elongated trough or retort into one end of which the fuel is delivered from a hopper by a suitable feeding device, such as a reciprocable ram. Air is discharged into the fuel by means of tuyères located along the upper margins of the retort. One or more reciprocable pusher blocks are provided in the lower portion of the retort for the purpose of moving the fuel along the retort and obtaining a proper distribution of the fuel as it is forced upwardly and laterally over the tuyères. These pusher blocks as heretofore constructed have been found erratic and undependable in operation in many installations. Particularly when the fuel is wet, or when a thick fuel bed is being maintained, the prior blocks have failed to move the fuel in the proper manner.

It is accordingly the main object of the invention to overcome these difficulties and to provide an underfeed stoker pusher block construction and arrangement which will operate efficiently even under adverse conditions.

It is a further object of the invention to provide a new and advantageous pusher block adapted for installation in the retort of an underfeed stoker and capable of feeding fuel in a desired manner despite the presence of excessive moisture in the fuel or the maintenance of a thick fuel bed.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a longitudinal section through an underfeed stoker furnace;

Fig. 2 is an enlarged view in section on the line 2—2 of Fig. 1;

Fig. 3 is a further enlarged plan view of the pusher block; and

Fig. 4 is a section on the line 4—4 of Fig. 3.

The embodiment illustrated comprises a furnace having a front wall 10, a rear wall 11, and an underfeed stoker retort 12 in the form of an elongated trough extending rearwardly from the front wall. The usual tuyère blocks 14 are mounted along the upper margins of the retort

to discharge air into the fuel, this air being supplied under pressure to the space beneath the retort and tuyère blocks in the customary manner by means of a suitable fan (not shown). A fuel hopper 15 is mounted in front of the front wall 10, and the fuel is delivered from this hopper into the retort by means of the usual reciprocable ram 16 actuated by any suitable means, such as the steam or hydraulic motor 18. A slideable pusher rod 19 of well known construction extends along the bottom of the retort 12 and through a guide boss 20 at the rear end thereof. The pusher rod is reciprocated through the medium of the usual lost-motion connection 22 between the ram 16 and the front end of the pusher rod.

In order to move the fuel rearwardly along the retort 12 and cause the fuel to be distributed in a desired manner as it moves upwardly and laterally over the tuyère blocks 14, one or more pusher blocks 25 are secured to the pusher rod 19 within the retort. The number and location of these blocks will depend upon the length of the retort, and in the stoker illustrated I have shown two of them. Each block is formed with a relatively steep rear pushing surface 26 and a gradually sloping front surface 27, as is customary, for the purpose of providing a positive rearward feeding of the fuel as the blocks move rearwardly, and minimizing the tendency of the blocks to drag the fuel forwardly during the return stroke. The pusher blocks are of less width than the retort.

It is found however that with prior stokers the fuel is not always distributed properly, this difficulty being more pronounced when the fuel is wet, or when a heavy fuel bed is being maintained. I have discovered that this difficulty results from the formation of arches in the fuel within the retort, these arches extending transversely from one side of the retort to the other directly above the pusher blocks. Thus the pusher blocks may operate in a void beneath the arches, with substantially no feeding action on the fuel. In order to prevent such arches from forming, each pusher block is provided with a pair of prongs or horns 29 which extend upwardly from the opposite side portions thereof. These prongs are rigidly connected to the pusher blocks, and they move forwardly and rearwardly along the side walls of the retort. Preferably the prongs flare upwardly and laterally to bring them close to the retort side walls. Since these side walls are the abutments against which the fuel arches tend to form, the loosening and agitation

of the fuel adjacent the side walls by the action of the reciprocating prongs is effective to prevent arch formation. The pusher blocks therefore operate within a solid mass of fuel, which they feed rearwardly in a desired manner. The prongs 29 themselves also have some feeding effect, which is enhanced by beveling their front surfaces to a sharp edge 30, thus permitting them to pass more readily through the fuel as they travel forwardly. In addition the prongs are inclined upwardly and forwardly so that during their rearward movement they will impart an upward and rearward shove to the fuel. The prongs of each pair are shown integrally connected at their lower ends by a transverse portion 31, thus providing a substantially U-shaped structure. This transverse portion 31 is of considerable width and it is rigidly attached to the top of the pusher block by means of two cap screws 32.

The operation of the invention will now be apparent from the above disclosure. The ram 16 will be reciprocated by the motor 18, delivering fuel from the hopper 15 into the front portion of the retort 12. The rod 19 and the pusher blocks 25, with their upwardly projecting prongs 29, will be reciprocated in a direction lengthwise of the retort by means of the lost-motion connection 22. The prongs 29 will loosen and agitate the fuel adjacent the side walls of the retort and thus prevent the formation of transverse arches in the fuel above the pusher blocks. The pusher blocks will accordingly be effective to feed the fuel rearwardly and distribute the fuel properly as it is forced upwardly and laterally over the tuyère blocks 14. The invention is simple, inexpensive, and highly efficient in operation.

Having thus described my invention, what I claim as new and desire to secure by Letters Patent is:

1. An underfeed stoker comprising a trough-shaped retort, means to supply fuel to the front end of the retort, a reciprocable pusher block located in the lower portion of the retort to advance fuel rearwardly along the retort, the pusher block having a relatively steep rear pushing surface and a gradually sloping front surface, means to reciprocate the pusher block, and a pair of prongs rigidly connected with the pusher block and extending upwardly for a substantial distance from the opposite side portions thereof and close

to the side walls of the retort to loosen the fuel and prevent the formation of transverse arches in the fuel above the pusher block.

2. An underfeed stoker comprising a trough-shaped retort, means to supply fuel to the front end of the retort, a reciprocable pusher block of less width than the retort located in the lower portion thereof to advance fuel rearwardly along the retort, the pusher block having a relatively steep rear pushing surface and a gradually sloping front surface, means to reciprocate the pusher block, and a pair of prongs rigidly connected with the pusher block and extending upwardly for a substantial distance from the opposite side portions thereof, the prongs flaring upwardly and laterally to bring them close to the side walls of the retort to loosen the fuel and prevent the formation of transverse arches in the fuel above the pusher block.
3. An underfeed stoker comprising a trough-shaped retort, means to supply fuel to the front end of the retort, a reciprocable pusher block located in the lower portion of the retort to advance fuel rearwardly along the retort, the pusher block having a relatively steep rear pushing surface and a gradually sloping front surface, means to reciprocate the pusher block, and a pair of prongs rigidly connected with the pusher block and extending upwardly and forwardly for a substantial distance from the opposite side portions thereof and close to the side walls of the retort to loosen the fuel and prevent the formation of transverse arches in the fuel above the pusher block.
4. As an article of manufacture, an underfeed stoker pusher block having a relatively steep rear pushing face and a gradually sloping front surface, and a pair of prongs rigidly connected with the block and extending upwardly for a substantial distance from the opposite side portions thereof.

5. As an article of manufacture, an integral U-shaped structure shaped for rigid attachment to the top of an underfeed stoker pusher block, said structure comprising a pair of upwardly extending prongs which flare apart in an upward direction, and a transverse portion of considerable width connecting the lower ends of the prongs.

ERIC H. SMITH.
